UNITED STATES PATENT OFFICE

96,841

DESIGN FOR A COMBINED TABLE AND STOOL UNIT

Frank Kelley, Cleveland, Ohio, assignor to A. Claus Manufacturing Company, Cleveland, Ohio, a corporation of Ohio

Application November 30, 1934, Serial No. 54,210

Term of patent 7 years

To all whom it may concern:

Be it known that Frank Kelley, residing at Cleveland, in the county of Cuyahoga and State of Ohio, has invented a new, original, and ornamental Design for a Combined Table and Stool Unit, of which the following is a specification, reference being had to the accompanying drawing, forming a part thereof.

The drawing is a perspective view of the article, showing my new design.

I claim:

The ornamental design for a combined table and stool unit, substantially as shown.

FRANK KELLEY.
